UNITED STATES PATENT OFFICE.

OERA D. LEWIS, OF RUSHVILLE, ILLINOIS.

PLAYING-CARDS.

1,062,720.

Specification of Letters Patent. Patented May 27, 1913.

Application filed April 8, 1912. Serial No. 689,185.

To all whom it may concern:

Be it known that I, OERA D. LEWIS, a citizen of the United States, residing at Rushville, in the county of Schuyler and State of Illinois, have invented new and useful Playing-Cards; and I do hereby declare the following to be a full, clear, and exact description of the invention, such as will enable others skilled in the art to which it appertains to make and use the same.

This invention relates to the art of games and the like, and particularly to a new and useful deck of cards for playing five different interesting games.

The primary object is to provide a card game, comprising a deck of cards distinguishably divided into suits, each provided with features or characters of designation, whereby each card of the respective suit may be distinguished, and also indicate the value thereof.

Another feature of the invention is to provide a card game comprising various features, which are hereinafter set forth, shown in the drawings and claimed.

In the drawings:—Fig. 1 is a view of the "motor suit." Fig. 2 is a view of the "auto suit." Fig. 3 is a view of the "horse suit." Fig. 4 is a view of the "trump suit." Fig. 5 is a view of the "cop suit." Fig. 6 is a view of the "mile suit."

Referring to the drawings 1 designates the "motor suit," each card of which is provided with a picture of a motorcycle, upon one face on each end of the card. The cards of the "motor suit" are numbered from 51 to 58 inclusive. The "auto suit" comprises eight cards numbered respectively from 1.01 to 1.08 inclusive. Upon each card of the "auto suit" upon each end thereof is the picture of an automobile 2. The "horse suit" consists of eight cards, each having a picture of a horse and sulky upon each end and numbered from 2.02 to 2.16 inclusive. The horse and sulky is designated by the numeral 3. The "trump suit" comprises eight cards. The "trump suit" is numbered from 1 to 8 inclusive, with the words "Auto," "Motor" and "Horse" printed upon each. The "cop suit" also includes eight cards, numbered respectively from 1 to 8 inclusive, each having a picture 4 of a policeman upon each end. The "mile suit" is distinguished from the other suits, by a picture of a sign board upon both ends of each card, which picture of the sign board is designated

by the numeral 5. The sign board of the first card of the "mile suit" has printed thereon the words "First mile," the next card of the suit "Second mile," and so on to 50 a "Seventh mile," which "mile suit" together with the joker (on each end of which a picture of a "purse" with "\$1,000" printed thereon is arranged), makes eight cards.

The various suits are as follows:—

Motor suit.	Auto suit.	Horse suit.	Trump suit.	Cop suit.	Mile suit.	
51	1.01	2.02	1	1	1st mile	
52	1.02	2.04	2	2	2nd mile	70
53	1.03	2.06	3	3	3rd mile	
54	1.04	2.08	4	4	4th mile	
55	1.05	2.10	5	5	5th mile	
56	1.06	2.12	6	6	6th mile	
57	1.07	2.14	7	7	7th mile	
58	1.08	2.16	8	8	Picture of a purse as joker.	75

It will be seen that this deck of cards comprises forty-eight (48) cards, including the joker, and the smaller the number on each card of each suit, the higher that card ranks in its respective suit, as for instance 51 80 "motor," 1.01 "auto," 2.02 "horse," and 1 "trump," and also 1 "cop" and the 1st mile of the "mile suit," which cards are the highest of each suit. The "joker" which makes the eighth card in the "mile suit" is 85 utilized as the highest card in the deck, and is played as a "trump" card with the "trump suit." The numbers on the "motor," "auto" and "horse" suits are supposed to represent the time a mile is 90 made on a race track, and serves to make the game true to its name, that is, when playing the game entitled "county fair."

The "trump suit" is, of course, higher in value than the cards of the other suits. Care 95 must be taken in selecting the proper cards in playing the different hereinafter named games, always using the cards called for, as explained in the directions of each game.

The various views in the drawings illustrate where the pictures and the numbers on the cards are printed, and the numbers are used in playing the game of "rambling."

The cards of the "motor suit" are distinguished by the picture of a racing motorcycle and rider, while the cards of the "auto suit" are distinguished by a racing automobile including a chauffeur, whereas the cards of the "horse suit" are distinguished by a racing horse hitched to a sulky including a jockey. No two cards of the same suit are numbered alike, although the de-

signs of the eight cards of each suit are the same. The designs on each card are correspondingly arranged upon each end, so that each card is always right end up. The 5 "joker" card has a design of a purse with the inscription

Purse
\$1,000

- 10 The "mile suit" is provided with a design as shown on the first card of said suit. Each card of the "trump suit" is provided with a racing horse and sulky on one end, with a racing automobile including a chauffeur on the other, in between which a racing motorcycle is arranged.

There are five different games played by this deck of cards, namely, "county fair," "bon-ton," "rambling," "goggles," and

- 20 "cop-'em."

The general rules for playing the game of "county fair," are as follows:—Select the following cards from the pack:—51, 52, 53, 54, 55, and 56 of the "motor suit"; 1.01, 25 1.02, 1.03, 1.04, 1.05, and 1.06 of the "auto suit"; 2.02, 2.04, 2.06, 2.08, 2.10, and 2.12 of the "horse suit"; 1, 2, 3, 4, 5, and 6 of the "trump suit," and the "joker" making twenty-five (25) cards. Dealer then shuffles the cards thoroughly and deals five (5) cards to each player and places the remaining five (5) cards face down upon the table; he then turns the top card face up, so that all players may see it; dealer may 35 then take this card and discard one from his hand for same if he thinks it will be of any help to him in playing; if he does not wish the card, he must turn it over so that its face will be down. The player sitting 40 to left of dealer plays first leading with any card he may choose; other players must play in turn and follow suit (play card same as one led) if possible. Card of highest value takes trick and player playing same, has 45 privilege of next lead. If a player does not hold a card of the suit which led, he may play any card he holds. It must be remembered that any card of the "trump suit" will take any card of either of the other 50 suits, and when "trump" cards are led, players must always play one if they hold any. The "joker" card will take any card (trumps included), and is counted a "trump" card; should it be the only 55 "trump" card a player holds, he must play it, should "trump" be led. Playing is continued until each player has played five (5) cards dealt him. The two players taking three of the five tricks may score one (1); should two players (partners) succeed in taking all five (5) of the tricks, they score two (2). Should a player be dealt a hand with which he thinks he can take all five of the tricks, he may try same after informing 60 other players; in such a case his partner

would not play. Should the dealer decide to take up the card which he turns face upward, after dealing five to each player, he and his partner must succeed in taking three of the five tricks, in order to score a point. Should the dealer and his partner fail to take three out of the five tricks, they are said to be "distanced," in which case their opponents score two (2). If a player playing for both he and his partner, take all five 70 tricks, he scores four (4). However, if he should take but three or four, he scores one (1), and should he fail to take three or more, his opponents score two (2). The players first scoring twelve (12) points are 80 the winners of the game called "county fair." This game is preferably for four players playing as partners, sitting opposite each other, as in the usual way.

The general rules for playing the game of "bon-ton" are as follows:—In playing "bon-ton" select the eight cards of each of the "motor," "auto," and the "horse" suits, and the seven cards of the "trump suit," including the "joker," making a total of 90 thirty-two, (32). The cards are then shuffled and cut, in order to ascertain the dealer, after which eight cards are dealt to each player, there being four players, playing alone or as partners. The player seated to 95 the left of the dealer plays first, leading with the card of his choice, and the other players play in turn. When a card of either the "motor," "auto," or "horse" suit is led, the other players may follow suit or "trump," 100 according to what he deems best to his interest. When a card of the "trump suit" is led, the other players must follow suit. If a player is unable to follow suit, when a "trump" card is led, he may play any 105 other card of the lowest value. The "joker" is the highest card in the game of "bon-ton," while the cards of the "trump suit" are next in rank, that is, in their 110 respective order. Any card of the "trump" suit will take any card of either of the "motor," "auto," or "horse" suits. A player taking a trick wins the lead for the next play. Each trick taken counts one (1), and if a player takes all eight tricks, he scores 115 eight (8) for the number of tricks, while 51 "motor," 1.01 "horse," and 2.02 "horse" cards count one (1) each, while the "joker" counts two (2), thus making a total of thirteen (13), which is possible to be made, upon one deal. As before stated the "joker" counts two (2), and is the highest card, and the trick taken by the "joker" counts one (1), in this way a player may make three in taking one trick. However, if 51 "motor," 1.01 "horse" and 2.02 "horse" cards are played, and then the "joker," a player may make six by the one trick.

The object of the players is to score 45, to 120 win the game.

The general rules of playing the game of "goggles" are as follows: To play the game of "goggles" select from the deck all the cards of the "motor," "auto," "horse," and "trump" suits, and the first seven cards of the "mile suit," including the "joker," thereby making a total of forty (40) cards. The cards of the "mile suit" are then placed upon a table in the following manner:

10

1	3	5	7
2	4	6	Joker

15 together with the "joker." Each player takes one suit of the remaining suits, and after each player has shuffled his respective suit, he deals two cards to each of the other players. In this manner each player will 20 hold eight cards composed of two of each of the other four suits. Players then bid in turn for the privilege of the first lead.

It is the object to score 45 to win the game. Eleven points is the highest that can be bid, 25 however each player bids the number of points he thinks is possible for him to make. If playing partners the points of each count to make 45. Player bidding highest plays the desired card upon the card "1st mile" 30 as shown in Fig. 7, and the other players play in turn, and must always follow suit. The player taking the card leads for the next play, and plays upon the card marked "2nd mile," the other players always following suit. This method of playing continues 35 until the cards are exhausted. The "mile" cards must be played upon in turn, as upon "1st," "2nd," "3rd," and "4th" miles and so on until the seventh mile, and then upon 40 the "joker." Each card taken counts one (1) for the player taking the same, excepting the "4th" mile card, which counts two (2), and the last card (the "joker") which counts 3 to the player taking it, thus making 45 a total of eleven points, that is, if one player takes all the tricks. Should a player fail to make the number of points bid, his opponents are allowed to score two (2), for every 50 one he lacks of making, for example, "A" bids 8, and he and his partner only make but 5, in which case the opponents score 2 for each one of the three they lack of making thus making a total of six, which added to the six points made by the opponents in 55 the first place, make a total of twelve. The cards are dealt and played in this manner, until 45 is scored, which are the winning points.

The general rules for playing the game 60 of "rambling" are as follows: Select all the cards of the "motor," "horse" and "trump" suits including the "joker" making a total of 38 cards. The cards are then shuffled and 8 dealt to each player, 65 the dealer placing the extra card face

downward upon the table. The player to the left of the dealer then states which way he wishes to ramble, choosing the suit that can be played to the best advantage. The next player, still going to the left, 70 then chooses his way of rambling, choosing a way not chosen by the other player, possibly the same way as the other player, provided he thinks it possible to succeed. The third player then chooses one of the 75 remaining two suits, as his way of rambling, thereby leaving dealer to ramble with the suit not chosen. The dealer may then take card on table and discard one for same, if he so desires; should it be the "joker" 80 or a card of the suit with which he is to ramble, he should retain it, and discard another. If the card is not desirable, he lays it to one side, and the game begins. Player choosing first, leads, playing the 85 card of his desire, preferably of his chosen suit, other players then play in turn, following suit if possible. When a player is without a card of the suit led, he may take the trick with a card of his chosen suit. 90 For example, suppose "A" should choose to ramble with the "auto" suit, leading with a card of that suit, "B" not holding a card of the "auto" suit, plays a card of his chosen "motor" suit (which is his way 95 of rambling, say for instance the card

Motor

33

thus taking the trick, unless "C" or "D" 100 do not hold a card of the "auto" suit, in which case either "C" or "D" may take the trick by playing the supposed highest card of their chosen suit. Had "C" chosen the "horse" suit, he is to play a card of 105 that suit, and should that card rank higher in its suit, than the card of "B" player, "C" will take the trick. Suppose "C" held the

Horse
2.04

110

of the "horse" suit, he would be victorious over "B's" play because

Horse
2.04

115

is the second highest card in its suit, while "B's" card ranks third in its suit. "D" might play a

Trump

120

card, because he may not have a card of the suit led, and having chosen the "trump" 125 suit, as his method of rambling, provided this should be the case, "D" would take the trick, for the reason that his card ranks higher than "C" or "B's" cards. The cards of the "motor," "auto," and "horse" 130

suits are numbered from 1 to 8 inclusive upon the design upon their faces. Should "B," "C," and "D" play cards of the suit led, but not ranking higher than "A," the 5 trick would belong to "A," and he should lead for the next trick. Should "B," "C," or "D" play a higher card of the suit led, the person playing such a card would take the trick and lead for next play. Each 10 player must always lead with a card of his chosen suit, as long as he holds them, then he may play any other card of his choice. The "joker" card will take any trick at any time, and the person holding it counts 15 it as a card of his choice. In this game the "trump" cards are of no higher value than the cards of the other suits. The player choosing the "trump" suit, makes known, by stating he will ramble by "hoboing," 20 while the other players disclose their choice, by stating they will ramble by "motor," "auto," or "horse." This game of "rambling" may be played by a party of four players, each for one's self, or as partners, 25 and the player or partners first scoring (45) forty-five wins the game. Each trick counts one to the player taking same, except the trick in which the "joker" is played, which "joker" trick counts two, which with the 30 other 7 tricks makes nine points to be made.

The general rules for playing the game of "cop-em" are as follows: From the deck select the five highest cards of each of the "motor", "auto", and "horse" suits, and 35 the eight cards, of the "cop" suit including the "joker" thus making a total of twenty-four (24) cards. The cards are shuffled and dealt to each player. The player to the left of the dealer plays first, and may lead 40 any card of either the "motor," "auto" or "horse" suits. The cards of the "cop" suit are not to be led, unless the player leading

holds no others. Each of the other players plays in turn and follow suit if possible. In case the other players can not follow suit, 45 they may play a card of one of the other two suits or else a "cop" card. Any card of the "cop" suit will take any card of either of the other three suits. The "joker" ranks as a "cop" card in this game, and is the highest 50 card of the "cop" suit, which are numbered consecutively from 1 to 8 inclusive. Number 1 of the "cop" suit, excepting the "joker" ranks the highest, and number 2 the next lowest and so on to the eighth card of the 55 "cop" suit. The player taking a trick leads for next play. Playing continues until cards are exhausted. Each "cop" card counts one to party holding it at the end of the playing of each deal. "Joker" counts two for the 60 player to whom it is dealt, as it is the best card, and can not be taken. Each trick without "cop" cards or the "joker" does not count. The object of this game is to make 10 points at the end of each deal. This game 65 may be played by four persons each for one's self, or as partners. The person or partners scoring forty (40) first wins the game.

The invention having been set forth, what is claimed as new and useful is:—

Playing cards comprising several suits, each of an equal number of cards, the cards of each suit being characterized according to their relative value, one suit being designated as a trump suit and a card of one of 75 the suits other than the trump suit being designated as a dominant card of the deck.

In testimony whereof I have signed my name to this specification in the presence of two subscribing witnesses.

ORA D. LEWIS.
